UNITED STATES PATENT OFFICE.

WALTER C. MOORS, OF OWENSBORO, KENTUCKY; WALTER Y. MOORS, ADMINISTRATOR OF SAID WALTER C. MOORS, DECEASED, ASSIGNOR TO SUE Y. MOORS, OF OWENSBORO, KENTUCKY.

IRONING TABLE.

Application filed March 3, 1925, Serial No. 12,936. Renewed March 26, 1928.

The present invention relates to ironing tables, and aims to provide an ironing board in combination with novel supporting means therefor, and enabling the structure to be 5 compactly folded together for storage or transportation.

Another object of the invention is the provision of separate means for supporting the opposite end portions of the board, the supporting means at one end of the board being capable of supporting the entire board, and the other supporting means being movable out of and into engagement with the board in order that clothes may be slipped over 15 and off the board conveniently.

A further object is the provision of an ironing table of the character indicated comprising a novel combination and arrangement of the component elements, in 20 order that the table will be convenient, practical and efficient in use.

With the foregoing and other objects in view, which will be apparent as the description proceeds, the invention resides in the 25 construction and arrangement of parts, as hereinafter described and claimed, it being understood that changes can be made within the scope of what is claimed, without departing from the spirit of the invention.

30 The invention is illustrated in the accompanying drawings, wherein—

Figure 1 is a side elevation of the table.

Fig. 2 is a bottom view thereof.

Fig. 3 is a perspective view of the table 35 when folded, in inverted position.

The table top comprises an ironing board 7 of suitable size, which is supported above a base 8 that rests on the floor. The base is composed of a pair of parallel longitudinal bars or beams 9, and cross bars 10, 11 and 12 secured to and across the lower edges of the bars 9. The cross bars 10 and 12 are at the rear and forward ends of the longitudinal bars 9, and the bar 11 is located 45 near the rear end bar 10. Said cross bars 10, 11 and 12 have their terminals projecting beyond the bars 9 in order to prevent the table from tilting side-wise, and are also preferably provided with rounded studs 13 50 to bear on the floor.

Two pairs of legs 14 and 15 support the rear or butt end portion of the board from the base, said legs or supports crossing one another, and the legs 14 and 15 at each side

are pivotally connected at their point of 55 crossing, as at 16. The lower ends of the legs 15 overlap the bars 9 at the outer sides thereof and above the cross bar 10, and said legs 15 are pivoted, as at 17, to the rear end portions of said bars 9. The legs 14 are disposed at the outer sides of the legs 15 and are hingedly connected at their upper ends with the rear end portion of the board 7. Thus, a transverse cleat 18 is secured to the bottom surface of the board 7 near the rear 60 end of the board, and has outstanding trunnions 19 at its ends fitted in apertures in the upper end portions of the legs 14. A cross bar 20 is secured to the forward edges of the legs 14 to hold them on the studs or 65 trunnions 19. The lower ends of the legs 14 have notches 21 to engage over the rear edge of the cross bar 11, and a cross bar 22 is secured to the upper end portions of the legs 15 to contact with the bottom surface 70 of the board above the cross bar 11.

A pair of legs or supports 23 is provided to support the forward or smaller end portion of the board, the lower end portions of the legs 23 overlapping the forward end portions of the bars 9 at the inner sides of said bars, and being pivoted to said bars, as at 80 24. A cross bar 25 is secured to the upper end portions of the legs 23 and serve as a yoke to connect said legs. Said bar 25 is 85 also adapted to contact with the bottom surface of the board at the forward end of the board, for supporting said end portion of the board. Transverse cleats 26 and 27 are secured to the bottom surface of the 90 board at the forward end thereof to receive the cross bar 25 between them, said cleats being bevelled at their opposite sides so that the bar 25 may ride readily under the cleats in swinging the legs 23 to upright position. 95 The cleats 26 and 27 are of a length slightly less than the distance between the legs 23 so that said cleats may be disposed between said legs.

When the table is erected, the top or board 100 7 is supported in a substantial manner by the legs so as to be capable of receiving considerable pressure without yielding, both the forward and rear ends of the board being supported directly underneath the same. 105 By slightly raising the forward end of the board 7, the front legs 23 may be swung, preferably forwardly as seen in dotted lines

in Fig. 1, away and spaced from the board to permit clothes to be slipped over and off the board conveniently. The board, it will be noted, is not encumbered between the 5 front and rear legs, so that clothes being ironed may pass around the board and underneath the same. When the front legs are released from the board, the rear legs 14 and 15 will support the board until the 10 front legs are again swung to upright position, the bar 25 readily passing under either cleat 26 or 27 to engage in the groove between said cleats. The rear legs 14 and 15 occupy very little space longitudinally of the 15 table, when the table is erected, but said legs will nevertheless support the board effectively while the front legs 23 are disengaged from the board, such as when placing clothes on or removing them from the board.

20 When folding the table, the board is swung upwardly to disengage the cleats 26 and 27 from the bar 25, and the legs 23 are then swung downwardly between the bars 9, the cross bar 25 being secured to the forward edges of the legs 23 so as to be disposed above the upper edges of the bars 9. By moving the board rearwardly slightly, the lower ends of the legs 14 are readily disengaged from the bar 11, and the legs 14 and 25 15 may then be folded forwardly, the legs 15 swinging forwardly and downwardly against the outer sides of the bars 9, and the legs 14 swinging in reverse directions to positions along the outer sides of the legs 35 15. The legs 14, 15 and 23 and bars 9 therefore hold together side by side in a common plane. The pivots 16 of the rear legs are nearer the lower ends of said legs than the upper ends thereof, in order that when 40 the table is folded, the cleat 18 will be located beyond the rear ends of the bars 9, as seen in Fig. 3. The bar 20 is secured to the forward edges of the legs 14 and the bar 22 is secured to the rear edges of the legs 14, so 45 that said bars will be disposed above and across the upper edges of the bars 9. The table can therefore be folded for compact storage or shipment.

Having thus described the invention, what is claimed as new is:—

1. An ironing table comprising a base, a board, supporting means for one end portion of the board connected with the base and foldable adjacent to the base, other supporting means hingedly mounted on the base to be disposed under the other end portion of the board, the first named supporting means having a hinge connection with the board to enable the board to be swung upwardly and also having a portion between 50 said hinge connection and secondnamed supporting means on which the board is seatable to support the board even though the secondnamed supporting means is disengaged from the board, the secondnamed supporting means having a cross bar at its upper end, and a pair of spaced transverse cleats secured to the bottom surface of the board to receive said cross bar between them and having their opposite sides bevelled to enable 55 the cross bar to pass readily under either cleat to a position between the cleats, the secondnamed supporting means being free to swing either outwardly beyond the corresponding end of the board or inwardly adjacent to the base under the board when said cleats are disengaged from said cross bar, the board when swung upwardly on the hinge connection being removable from said portion of the firstnamed supporting means 60 and from said cross bar.

2. An ironing table comprising a base having longitudinal bars and cross bars below and secured to said longitudinal bars, and supports crossing one another and pivotally connected, one support being hingedly connected to the longitudinal bars of the base and having a portion at its upper end to contact with the bottom of the board, the other support being hingedly connected to 65 the board and having notches at its lower end to engage one of said cross bars.

In testimony whereof I hereunto affix my signature.

WALTER C. MOORS.
